UNITED STATES PATENT OFFICE.

ROBERT C. FINGAL AND THOMAS FABRIN, OF AURORA, ILLINOIS.

PANE-ATTACHING MEANS.

No. 849,112.

Specification of Letters Patent.

Patented April 2, 1907.

Application filed July 11, 1906. Serial No. 325,598.

To all whom it may concern:

Be it known that we, ROBERT C. FINGAL and THOMAS FABRIN, citizens of the United States, residing at Aurora, in the county of 5 Kane and State of Illinois, have invented new and useful Improvements in Pane-Attaching Means, of which the following is a specification.

The invention relates to an improved 10 means for attaching glass panes to structural metallic framing, comprehending specifically a construction of framing whereby to fixedly secure the panes in place without the use of the ordinary screws.

15 The invention is primarily designed for securing the heavy glass panes used in display-windows, the main object residing in the provision of a fastening means for securing the panes to the structural frame against possibility of disconnection, the specific details of 20 the securing means permitting the ready insertion or removal of the pane in a convenient and expeditious manner.

The invention will be described in the following 25 specification, reference being had particularly to the accompanying drawings, in which—

Figure 1 is a broken front elevation illustrating the application of the glass panes to 30 the central bar of the window structure. Fig. 2 is a rear elevation of the same. Fig. 3 is a transverse section on the line 3-3 of Fig. 1. Fig. 4 is a broken sectional view showing a modified form of securing means.

35 Display-windows of the type to which the invention applies are, it will be understood, made up of structural metallic strips, which in the case of a comparative small window outline the form and shape of the window. The 40 larger windows, however, as in store windows or the like, are ordinarily provided with a vertically-disposed centrally-arranged strip which divides the frame in two parts, and the central strip is arranged to receive the side 45 edges of the panes making up the window.

As shown, the improved securing means is 50 illustrated in connection with the central strip of the frame, which, as stated, is adapted to support the two panes, though it is to be understood that the invention is intended and designed for application to the end and side strips, though the latter are adapted for supporting the edge of but a single pane, as will be evident.

55 The window-frame is made of sheet-metal strips ornamented to the desired degree, the

central strip 1 being illustrated. This strip comprises a face 2, which may be ornamented to any desired degree, and is formed at the edges with side strips or faces 3, extending at right angles to and inwardly from the face-strip. At the inner edges of the side faces are formed laterally-projecting flanges 4, which extend throughout the length of the side faces and are designed to form the inner 60 rest or support for the glass. The flanges 4 extend in parallel relation to the face of the strip and may be of any width desired, though preferably just sufficient to form a substantial support for the glass. At determinate intervals throughout the length the flange 4 is provided with openings 5, preferably disposed immediately adjacent the junction of said flange with the side face of the strip. 70

A securing-section 6, also of sheet metal and preferably shaped to provide an ornamental finish, is formed with a relatively inner edge 7, designed in use to rest snugly against the side face 3 of the frame-strip. 75 From the portion 7 of the securing-section project pins 8, formed in their inner or free ends with openings 9. The pins are equal in number to the openings 5 in the flanges 4 and so disposed relative to the length of the 80 securing-section that when said section is in place the pins are adapted to register with and pass through said openings 5.

In securing the glass 10 in place the proximate edge thereof is placed against the 85 flange 4 of the frame-strip and the securing-section brought into contact with the opposite face of the glass, the fingers 8 passing through openings 5 in the flange-plate. Keys 11 are then inserted in the openings 9 90 in fingers, the proximate surface of the flange 4 being preferably cut out, as at 12, for the reception of the key. The securing-section is thus locked relative to the flange 4, and as the edge of the glass is snugly held 95 between said section and flange independent movement thereof or possibility of disconnection is prevented.

If preferred, the glass faces instead of being directly engaged by the flange 4 and securing-section may be protected by intermediate layers of shock-absorbing material, as putty or the like, as 13, to avoid a jar or blow to the window-frame being transmitted directly to the glass. 100

In Fig. 4 the structure is similar to the shown in the preferred form except that

the pin 8 is threaded at the free end and is engaged beyond the surface of the flange 4 with a nut 14, whereby to secure the securing-section in place.

5 It is of course to be understood that the side strips of the window-frame are formed for the reception of one edge of the glass pane only, which connection is a duplicate of that described for one side of the central strip.

10 The rear wall of the opening 9 in the fingers 8 is so disposed relative to the rear surface of the flange 4 that the key 11 in being driven to its seat will exert a wedge and drawing action upon the fingers, thereby binding the 15 securing-section tightly in place to prevent possibility of movement of the glass.

The construction described provides for the ready securing of the glass in place in a manner to maintain the full ornamentality of

20 the structure and yet to provide for the ready and convenient disconnection of the window-frame when desired to permit the withdrawal of the glass. It is to be particularly noted that no screws or other relatively fixed

25 securing means are used and that the keys 11 in the preferred form and the nuts 14 in the modified form provide, in effect, the sole means for holding the glass in place. Therefore the glass is free for ready and con-

30 venient removal upon the disengagement of these securing means.

We claim—

1. A window-casing comprising metallic strips, each of said strips being formed with 35 a laterally-projecting pane-supporting flange, and a securing-section to coöperate with said flange, said section being formed with

means to engage the flange at determinate points throughout the length of the latter.

2. A window-casing comprising metallic strips, each of said strips being formed with a pane-supporting flange, a securing-section for each flange, strips projecting from the section at determinate points throughout its length and adapted to be passed through 45 openings formed in the flange, and means for engaging the strips beyond the flange.

3. A window-casing comprising metallic strips, each of said strips being formed with a pane-supporting flange, a securing-section 50 for each flange, strips projecting from the section at determinate points throughout its length and adapted to be passed through openings formed in the flange, and keys arranged for removable engagement with the 55 strips beyond the flange.

4. A window-casing comprising metallic strips, each of said strips being formed with a pane-supporting flange, a securing-section for each flange, strips projecting from the 60 section at determinate points throughout its length and adapted to be passed through openings formed in the flange, and keys arranged for removable engagement with the strips beyond the flange, the coöperating 65 surface of the flange being cut away to provide for the reception of the keys.

In testimony whereof we affix our signatures in presence of two witnesses.

ROBERT C. FINGAL.
THOMAS FABRIN.
